UNITED STATES PATENT OFFICE.

MAURICE LEVISON, OF CHICAGO, ILLINOIS, ASSIGNOR TO CHICAGO SIGNAL COMPANY, OF CHICAGO, ILLINOIS, A CORPORATION OF ILLINOIS.

SIGNALING-INSTRUMENT SET.

1,128,013.

Specification of Letters Patent.

Patented Feb. 9, 1915.

Original application filed May 27, 1912, Serial No. 699,856. Divided and this application filed March 6, 1914. Serial No. 827,017.

To all whom it may concern:

Be it known that I, MAURICE LEVISON, a citizen of the United States, residing at Chicago, in the county of Cook and State of Illinois, have invented certain new and useful Improvements in Signaling-Instrument Sets, of which the following is a specification.

My invention relates to improvements in signaling instrument sets, and more particularly, in some of its details, to an instrument set adapted to constitute part of a hospital signaling system of the general character described in my copending application, Serial No. 699,856, filed May 27th, 1912.

One of the objects of my invention is to provide a signaling unit in the form of a self-contained instrument set, which may be all assembled at the factory ready for connection to the line wires that run to the source of electrical supply and the remote signaling lamps or other annunciators.

A further object of my invention is to provide such an instrument set embodying in its unitary structure all of the switches, relay parts and associated mechanical devices required for the signal service of a single station; in compact, neat, and attractive form, and susceptible of ready installation in conjunction with the ordinary outlet boxes, or "wall boxes" customarily employed in commercial installation of electrical appliances in buildings.

Another object of my invention is to provide a signaling instrument set which is simple in construction, cheap, easily manufactured, durable, and not liable to get out of order.

Another object of my invention is to provide a novel and advantageous construction and arrangement of the annunciator-controlling switch-means, and the electro-mechanical and mechanical controlling devices for such switch-means.

A further object of my invention is to provide an improved connection between the exterior signal-setting switch, which usually is a pendant push-button and the fixed electrical appliances of the set; and generally and in detail to improve the construction and arrangement of signaling apparatus of the character described.

Other and further objects of my invention will become apparent to those skilled in the

art from the following description taken in conjunction with the accompanying drawings, in which—

Figure 1 is a front elevation showing the external appearance of an instrument set, of simple form, embodying my invention. Fig. 2 is a central, vertical section on line 2—2 of Fig. 1; Fig. 3 is a diagram of electrical connections. Fig. 4 is a transverse section on line 4—4 of Fig. 2; Fig. 5 is a detail of relay parts; Fig. 6 is a detail of the relay armature; Fig. 7 is a detail section on line 7—7 of Fig. 4. Fig. 8 is a detail of the signal release button; Fig. 9 is a detail of a modification of Fig. 4; Fig. 10 is a front view of a modified structure embodying my invention; Fig. 11 is a section on line 11—11 of Fig. 10; and Fig. 12 is a detail view of the nut plate.

In certain signaling installations, as in hospital signaling, it is important that there shall be at suitable places relatively remote from the signal-initiating station (which is, say, at the patient's bed) signal lamps or other annunciators electrically controlled for the setting and release of their signals by different instrumentalities at the signal-initiating station. The signal-setting switch should be located for operation by the patient, and the means for release of the signal should be located adjacent to the setting means, in the neighborhood of the signal initiating switch, (as at the bed-side of the patient), but said releasing means is not intended to be operated by the patient. By such an arrangement it is insured that a signal, once set by a patient, may not be erased until an attendant comes to the point where the signal was set and effects the releasing operation. My copending application above referred to illustrates a system of this character which has the important advantage of operability by alternating, as well as by direct, current, and which involves in the systemic arrangement apparatus of the character forming the subject matter of this application. The present application is, therefore, as to such constructional features, hereinafter claimed, as are illustrated in my said system application (but not susceptible of being separately claimed therein) a division of said application.

In Fig. 3 of the drawing herein I illustrate, schematically, a fragment of a signaling system, from which the general purpose

and operation of the present apparatus easily may be gathered. In said figure, 19 indicates a relay whereof 20 is the magnet and 21 its armature. This armature in its two positions respectively locks and frees the stem of a release member 22 which coacts with a spring-switch, generally indicated at 23. This switch has spring leaves, closed normally, arranged in circuit with the magnet 20 and with a push button 24, which in practice is a pendant switch suitably disposed for convenient operation by a patient. When the push button 24 is pressed closing the circuit for magnet 20 through leaves of switch 23, said magnet attracts its armature 21, and frees the release button 22 which is thrown forward by the main leaf of the switch 23 as the latter springs forward, opening the circuit for the magnet 20. 10 Switch 23 also has normally open leaves, connected with suitable annunciator lamps 124, 124^a, etc., and when the main leaf springs forward the circuits for these lamps are closed. The various electrical circuits, 15 of course, include suitable line wires energized by any suitable source of current supply such as the alternating current generator 25 operating through a step-down transformer 26; it being my preference that the apparatus herein described shall be so constructed as to operate on alternating current of relatively low voltage—say 10 volts.

When once the signal annunciators 124, 124^a, etc., appurtenant to the instrument set, 20 are energized they remain in active condition until the release member 22 is pressed inwardly, thereby operating the switch 23 to open the annunciator circuits and again to close the switch leaves in the circuit of the magnet 20. When the release button is so pressed, the armature 21 again latches it in its signal-releasing position against the tension of the main switch spring, and thus the apparatus is all restored to normal condition. 25

Referring now to the particular construction illustrated in the drawings 30 indicates in general a metal face plate, or wall plate, preferably of suitable dimensions to coact with some standard electric outlet fitting, and having mounted on the back thereof an insulating base 31, secured thereto by screws 31'. The relay spring, switch, etc., are mounted on such base, said relay parts being 30 preferably mounted on a metallic relay-base 32, secured to the insulating base by screws 32'.

As best shown in Fig. 5 the relay base 32 may be the magnet yoke, and it carries the 35 two cores 33 of the electromagnet 20, projecting rearwardly at right angles therefrom and arranged in vertical alinement with each other. The cores 33 are preferably secured to the base 32 by screws 34 and each 40 core is preferably notched near its outer

polar end, as at 35. Preferably the base yoke 32 also has at its upper portion a guiding aperture 36 and at its lower extremity an inturned or rearwardly extending lug 38. 70

The magnet cores preferably carry the armature of the magnet 20, through the intermediary of a non-magnetic yoke 39 (Fig. 5) by which they themselves are united and spaced. This non-magnetic yoke, which 75 may be made of brass, is provided with a key hole slot 40 and an open notch 41, adapted to coact with the notches 35 in the sides of the pole cores 33. It also has a guiding aperture 36' at its top, and integral 80 side arms 42 to afford support for the armature to be described.

The magnet parts indicated in Fig. 5 may readily be assembled by mounting on the cores their respective windings, slipping 85 the core notches 35 into engagement with the yoke-slots 40—41, and then screwing the cores to the base yoke 32. In this way the magnet parts are very rigidly and compactly secured together and an effective support for the armature is provided. 90

The armature 21, shown in detail in Fig. 6, has a plate portion 45 confronting the magnet poles and an inturned latch extension 46 above the pivotal point, directed 95 forwardly over the magnet and terminating with a down-turned, latch nose 47 having its end rounded in cross-section. In alinement with the apertures 36—36' said armature structure is provided with an aperture 46'. 100 The rearwardly extending arms 48 of the armature fit between the arms 42 of the supporting yoke 39 and are pivotally secured thereto by a suitable pintle. The armature is normally retracted by a spring 45' secured to lug 38 and acting against the free end of the armature. 105

The release-button member 22 with which the latch extension 46 of the armature cooperates, has a stem 51 provided with an 110 encircling groove 52 to receive the rounded nose 47 of the armature latch extension 46, and said stem is reduced at its ends to slide in, and rotate in, the apertures 36—36' in the base yoke 32 and non-magnetic yoke 39. 115 The forward end of the stem 51 extends through suitable guiding openings in the insulating base 31 and the wall plate 30 to receive the insulating push button or head 53, screw threaded thereon. The shoulders 120 formed by the rear extremity of this head 53 and the larger body part of the stem, lie on opposite sides of the intervening plate 32, and act as stops positively to limit the movement of the release button in both directions as will be apparent in Fig. 2. The reduced rear end of the stem 51 extends through the aperture 46' in the armature and bears an insulated tip 55 for coaction 125 with the control switch 23. Switch 23 is 130

preferably made up of a number of vertical spring leaves, as 23^a, 23^b, 23^c, 23^d and 23^e (number depending on number of lamps to be controlled) mounted at their lower ends 5 on an insulating foundation 50' which is carried by an L shaped arm 56 secured as at 57 to the lug 38 of the base yoke 32. Arm 56, as best shown in Fig. 2, may also act to anchor the armature spring 45' heretofore referred to.

The members of the switch 23 are herein shown as five in number the penultimate spring 23^b being longer than its fellows and coacting with the insulated tip 55 of the 15 release-member stem. When said stem is freed from restraint of the armature-latch the spring 23^b forces said stem forward to the position shown in Fig. 2, and thereby also the spring 23^b breaks contact with the 20 rearmost spring 23^a and closes contact between itself and the several forward springs indicated as 23^c, etc. When the release member 22 is pressed rearwardly and latched by the armature, it deflects the spring 23^b rearwardly into contact with the spring 23^a, 25 and allows the forward springs 23^c, etc., to spring apart, so opening the connections of all the lamps 124, 124', etc., (Fig. 3) which are controlled by said switch and closing at 30 said controlling switch only the connections for the magnet 20.

I find that the construction herein before described provides a very sensitive and efficient electrically-released and manually-reset switch. The coöperating armature lever latch and grooved release button stem provide a delicate but efficient latch, such that energization of the electromagnet 20 instantly frees the release button, but such 40 that the button is securely held in latched position as long as the magnet remains de-energized. The rounded nose of the latch is substantially free from the effect of wear, and releases easily and the edge shoulder of 45 the groove 52 in the stem is effectively safeguarded against wear by the rotatability of the stem as a whole, said stem turning, more or less of course, under the pressure of the hand of the operator, thereby insuring 50 in the course of time substantially equal wear on all parts of the edge of its latch receiving groove.

Upon the insulating base 31 are mounted 55 clips 59 arranged beside the base yoke 32 and suitable in number and arrangement to afford connection between all exterior wires and the electrical parts mounted on the base.

The insulating base 31 has coöperating therewith an insulating cover 60 closed 60 throughout on five sides and acting as a housing for the mechanisms carried on the base. As shown in Figs. 2 and 4 the front of this housing is preferably co-extensive with the insulating base 31, and makes close 65 contact therewith throughout its perimeter,

while at its back the casing has a vertical extension 60' narrower than the forward portion of the housing and adapted to receive only the relatively narrow switch structure 23 with its connecting wiring. 70 The wiring running from the interior of the housing, to the line wires that are to be brought to the rear of the housing, may be run through apertures, as at 61 (Fig. 4), arranged in the shelves or shoulders flanking 75 the extension 60'. This construction advantageously provides free spaces flanking the extension 60' into which the line wires may be brought with ample room for effecting connections, even if the structure 30 be installed in an outlet box as small as will will receive the body of the housing 60. The housing 60 is secured to the insulating base 31 by long screws 63 taking through the corners of the housing, and through apertures in the corners of the insulating base 31, for thread engagement with nut plates 65, which, as best shown in Figs. 7 and 9, are preferably sector-shaped and located in appropriate recesses 66, in the front face 35 of the base 31.

For connection of the cord of the pendant switch 24 with the relay mechanism, I provide detachable locking connection physically suspending the cord from the face 95 plate. A nipple shell 70, is screw threaded as at 71 into a suitable aperture in the face plate 30 and is provided with a throat 72, through which the cord 24' is run. Just inside of the throat the cord is preferably 100 knotted or otherwise provided with an enlargement 24^a so that any linear strain on the cord is transmitted to the nipple 70 and not to the wiring connections between the cord-wire ends and the appropriate terminals. In many installations it is desirable 105 that the signal initiating cord shall be readily removable and replaceable, by those in authority, and to facilitate such removal and replacement I preferably employ, as indicated in Fig. 4, a plug switch construction, for effecting connection of the cord end with the wiring terminals on the base. In such construction 73 indicates a plug member having the two split pins 74 respectively 110 taking into sleeves 75 which are permanently secured in the insulating base 31 and which receive the connections of the appropriate interior wires. The plug switch thus provided is very small and is neatly housed 115 in the nipple 70. By screwing the nipple tightly in place with a suitable spanner or other special tool,—for reception of which apertures 70' may be made in the nipple 70,—the nipple and its connected cord and 120 pendant switch are locked or made proof against accidental displacement or removal by the mere use of the fingers, although readily removable by the special tool. As 125 shown in Fig. 9, the same construction with- 130

out the plug switch may be employed, with some slight saving of expense, by running fixed wiring terminals or binding posts 76 directly through the insulating base 31, and 5 directly connecting the ends of the cord wires to these binding posts within the nipple 70.

The face plate 30 with its connected part may be mounted on the conventional cap 81 10 of an ordinary outlet box 82 of any desired design.

In many instances, particularly in the wards of hospitals, where a number of patients will be quartered, there should be provided 15 a bed lamp in addition to the ward-room-door lamp, and the pilot lamp, and any other signal annunciators, in order that the attendant, reaching the ward, may observe which patient initiated the call. In 20 such constructions the bed lamp is most conveniently placed in conjunction with the wall plate, and in Figs. 10 and 11 I have shown a construction to this end. The wall plate 30^a in such an equipment is made 25 transversely larger than in the simpler construction shown in Fig. 1. The relay and its equipment are mounted as hereofore described, and beside the relay housing 60 the lamp is mounted. 85 indicates a lens 30^a movably mounted in opening 86 in the plate 30^a, and having in rear thereof the bed lamp 124^a. The socket base generally indicated at 88 is carried on a yoke 89 secured as by screws 90 to the face plate 30^a. In the particular 35 construction shown the socket shell 91 is mounted centrally in an annular insulating ring 92, the forward end of which abuts against the vertical member of the yoke 89, and a bushing collar 93 threaded on 40 the socket shell 91 has an extension through the yoke member, so that it separates said part 91 from the yoke 89 and forces a rubber washer 94 into clamping coöperation with the forward side of the vertical member 45 of the yoke. I find in practice that this form of mounting is stable and efficient.

It will be understood, of course, that the connections between the electrical parts of the set are made in assembling the structure, and that stub-wires for connection with the line wiring are run out of the casting 60, leaving only the connections with the mains to be made within the outlet box, when a unit is connected in a system.

55 While I have herein described in some detail a particular embodiment of my invention which has been found to be satisfactory and effective in practice, for purposes of full disclosure thereof it will be understood by those skilled in the art that many changes in details of construction and arrangement might be made without departure from the spirit of my invention and within the scope of the appended 60 claims.

Having described by invention, what I claim is:—

1. In an instrument of the character described, the combination of a base structure, a relay mounted thereon comprising 70 a magnet, its armature, and a switch, a release member extending through said base structure and coöperating with said switch to be projected by said switch, and a latch member movable by said relay armature for 75 holding said release member at one extreme of its range of movement, to restrain it against projection, when the armature is retracted.

2. An instrument set of the character described comprising, in combination, a supporting structure; a relay supported thereby, comprising a magnet, a pivoted armature for said magnet, carrying a forwardly extending latch, and a spring switch in rear 80 of said magnet; a pendant switch, connected with said supporting structure and operable from in front thereof, electrically connected with the relay magnet to control it; a release member extending through said supporting structure and coöperating with the spring switch, said releasing member arranged to be latched in rearmost position by the armature-latch when the armature is retracted. 95

3. An instrument set of the character described comprising an insulating base, a relay carried by said insulating base comprising an electromagnet, extending rearwardly from the base, a pivoted armature in rear of said electromagnet, and a spring switch in rear of said armature, a releasing member extending through the base and coöperating with the spring switch, said member being pressed forwardly by the spring tension of 100 a part of said switch and coöperating with said armature to be latched thereby in rearmost position when the switch spring is under tension and the armature is retracted. 105

4. In an instrument set of the character described the combination of a base plate; an insulating base mounted thereon; an electro-magnet carried by said insulating base; an armature therefor; an armature-operated latch; a releasing means extending through 110 said base and base plate, coöperating with said armature-operated latch to be held thereby in rearmost position when the armature is retracted; and a spring switch, co-operating with said releasing means, where- 115 in the switch elements are forced to one position by the movement of the releasing means to rearmost position, and move said releasing means to forward position when the armature is attracted to free said releasing means. 120

5. In an instrument set of the character described the combination of a base plate; an insulating base mounted thereon; an electro-magnet carried by said insulating base; 125

- an armature therefor; an armature operated latch; a releasing means extending through said base and base plate, coöperating with said armature-operated latch to be held thereby in rearmost position when the armature is retracted; a spring switch, coöperating with said releasing means, wherein the switch elements are forced to one position by the movement of the releasing means to rearmost position, and move said releasing means to forward position when the armature is attracted to free said releasing means, and a pendant push button switch connected with said relay magnet to control the operation thereof.
6. In an instrument set of the character described the combination of a face plate, an insulating base mounted thereon, a relay comprising an electromagnet, its armature and a spring switch comprising a plurality of leaves, one extended beyond its fellows, a releasing member extending through said base plate and base and coöperating with said extended switch-leaf to control the movement of the spring switch and to be projected thereby when unlatched, said releasing means arranged in latching coöperation with the armature to be latched thereby in one position when the armature is retracted and freed when the armature is attracted.
7. In an instrument set of the character described the combination of a face plate; an insulating base mounted thereon; an insulating cover carried by said base; a relay on said base housed within said cover, comprising a magnet, its armature, and a spring switch; an armature operated latch; a pendant push button secured with respect to said base plate and electrically connected to control the relay magnet; and a push button release member extending through said face plate, coöperating with the spring switch to control it, and also coöperating with the latch armature operated to be controlled thereby.
8. In an instrument set of the character described, the combination of an insulating base, an electromagnet secured thereto extending rearwardly therefrom, an armature for said magnet, having a forwardly projecting latch extension terminating in a down turned rounded nose, a horizontally reciprocable stem extending through said insulating base for manual repression from in front thereof, said stem provided with a groove for coöperation with the latching nose of the armature, and a circuit switch controlled by said release stem.
9. In an instrument set of the character described, the combination with an insulating base, a magnet mounted thereon comprising cores, windings thereon, a non-magnetic yoke connecting the polar ends of said cores and provided with a guiding aperture, an armature mounted in said non-magnetic yoke provided with a forwardly extending latch, a release stem guided in the non-magnetic yoke and extending forwardly through the insulating base, said release stem having a groove therein for coaction with the armature latch, and a spring switch controlled by and controlling the rearward and forward reciprocating movements of said release stem.
10. In an instrument set of the character described, the combination of an insulating base, an electromagnet thereon comprising core members, a yoke connecting said core members and provided with a guide aperture, a non-magnetic yoke connecting the opposite ends of said core members and provided with a guide aperture, windings on said cores between said yokes, an armature mounted on said non-magnetic yoke and having a forwardly projecting latch extension, and an aperture alining with said yoke-guide-apertures, a release member extending through said guiding apertures in said two yokes and the armature aperture and beyond the insulating base for operation from the front thereof, said stem provided with an annular groove for coöperation with the latching extension of the armature, and a spring switch coöperating with the rear extremity of said stem.
11. In an instrument set of the character described, the combination of a relay comprising in combination magnet cores, a yoke member therefor having a rearward extension at one end and a guiding aperture at the other end, a non-magnetic yoke secured to the polar extremities of said cores, and provided with rearwardly extending arms, an armature mounted on said arms, provided with a forward latch extension having a down turned nose, an armature spring mounted on the rearwardly projecting portion of the first said yoke, a spring switch mounted on said extension, and a release member comprising a stem rotatably mounted in said guiding apertures in the magnet yokes coöperating with said spring switch and provided with an annular groove for coöperation with the nose of the armature latch.
12. In an instrument set of the character described, the combination of a face plate; an insulating base mounted thereon; a relay mounted on said insulating base comprising a magnet, an armature, and a spring switch in rear of said magnet; a releasing member comprising a stem extending through the insulating base and face plate, coöperating with said spring switch and coöperating with the magnet armature to be latched or released by the latter, and a housing for said relay structure having a wider portion enveloping the magnet, and

- a narrower portion enveloping the spring structure and affording wiring spaces beside said extension in rear of the broader portions of the housing.
- 5 13. In an instrument set of the character described, the combination of a metallic face plate; an insulating base mounted thereon; a relay mounted on the insulating base comprising an electromagnet, its 10 armature and a spring switch; means extending through said face plate coöperating with the spring switch to move the latter in one direction, and coöperating with the relay armature to be latched thereby;
- 15 a nipple secured to said base plate, a pendant switch having a cord extending into said nipple and secured in the interior thereof and wiring connections from said core to said magnet.
- 20 14. In an instrument set of the character described, the combination of a face plate,
- having a glazed orifice, a signal lamp mounted in rear of said orifice, an insulating base connected to the rear side of said base plate, a relay mounted on said insulating base, comprising an electromagnet, its armature, a spring switch controlling the signal lamp, a releasing member extending through the face plate controlling said switch and coöperating with the relay magnet to be latched thereby in position to open the switch for said latch, and a switch accessible from the front of the face plate connected with said relay for controlling the operation thereof. 25 30 35

In testimony whereof I hereunto set my hand in the presence of two subscribing witnesses.

MAURICE LEVISON.
